UNITED STATES PATENT OFFICE.

FANNIE FAIRLEY AND ELEANOR E. GUNSTON, OF WILKINSBURG,
PENNSYLVANIA.

DESIGN FOR AN ASH-PAN.

SPECIFICATION forming part of Design No. 26,151, dated October 6, 1896.

Application filed August 5, 1896. Serial No. 601,813. Term of patent 7 years.

To all whom it may concern:

Be it known that we, FANNIE FAIRLEY and ELEANOR E. GUNSTON, citizens of the United States of America, residing at Wilkinsburg, 5 in the county of Allegheny and State of Pennsylvania, have invented certain new and useful Designs in Ash-Pans, of which the following is a specification, reference being had therein to the accompanying drawings.

15 This invention relates to designs for ash-pans, and in describing the invention in detail reference is had to the accompanying drawings, forming a part of this specification, and wherein like letters of reference indicate 15 similar parts throughout the several views, in which—

Figure 1 is a side elevation of our design for an ash-pan. Fig. 2 is a top plan view of the same, and Fig. 3 is a front view.

The principal feature of our design is the 20 pan or box *a*, having a rounded or semicircular front *b* of greater width and height than the box, said front *b* provided with a knob *c* and at each side of same with ventilators *d d*. A bale *e* is secured to the box *a* for convenience in handling. 25

Having fully shown and described our invention, what we claim is—

The design for an ash-pan, substantially as herein shown and described. 30

In testimony whereof we affix our signatures in presence of two witnesses.

FANNIE FAIRLEY.
ELEANOR E. GUNSTON.
